UNITED STATES PATENT OFFICE.

JOSEPH E. RALPH, OF NEWARK, NEW JERSEY.

FILING-ENVELOP.

1,132,972.

Specification of Letters Patent. Patented Mar. 23, 1915.

Application filed November 3, 1913. Serial No. 799,052.

To all whom it may concern:

Be it known that I, JOSEPH E. RALPH, a citizen of the United States, residing at Newark, in the county of Essex and State 5 of New Jersey, have invented certain new and useful Improvements in Filing-Envelops; and I do hereby declare the following to be a full, clear, and exact description of the invention, such as will enable others 10 skilled in the art to which it appertains to make and use the same.

This invention relates to envelop containers for use in cases in cabinets of both the ordinary and automatic styles for house 15 talking machine disk records vertically filed correspondence or records, and any matters such as are or may be found convenient to keep in such manner.

The automatic receptacles referred to are 20 more particularly those shown in my Patent No. 857,202 issued June 18, 1907, and in my pending application Serial No. 462,143, filed November 11, 1908. This invention affords an extension to the usefulness of the matter 25 disclosed in said application.

An object of the invention is to provide containers which normally hold the largest size 30 of matter to be filed, while there may be added to the container means for conveniently filing, matter smaller than the largest size to be filed, the particular matter filed in the present application being disk records and envelopes for containing correspondence, etc.

A further object of the invention is to 35 provide a container having the general form of an envelop wherein a portion of the front of the envelop is free from the back of the envelop, and a suitable textile stay at the point where the front and back of the envelop are connected.

With these and other objects in view, the invention consists in certain constructions, combinations and arrangements of the parts which will be hereinafter fully described 45 and claimed.

In the accompanying drawing wherein similar reference characters designate corresponding parts: Figure 1 is a front elevation of the envelop container showing a 50 record therein; Fig. 2 is an edge view of the container seen in Fig. 1; Fig. 3 is a central vertical section of the container shown in Fig. 1, the section being taken parallel to the face of the disk; Fig. 4 is a vertical central 55 section taken on line 4—4 of Fig. 1; Fig. 5

is a view showing a container for smaller sized records as applied to a larger container a portion of the latter being shown in section; Fig. 6 is an enlarged side view of the metallic strip mounted upon the bottom of 60 the container shown in Fig. 5; Fig. 7 is an enlarged perspective view of a modified form of the base forming a part of the container; Figs. 8 and 9 show positioning members which may be applied to the form of the invention shown in Figs. 1 to 4; Fig. 10 is a perspective view of the stay used on the container; Fig. 11 is an enlarged vertical sectional view taken through a large envelop containing an auxiliary envelop. 70

The general aim of the present invention is to provide a number of containers or envelopes of standard size which carry a large size disk or other matter and are housed in a suitable cabinet, suitable selecting devices 75 being applied to the container. When it is desired to use the standard size envelop as the container for holding the smaller size disks, there is provided a supplementary container which fits within the standard 80 container and is so proportioned as to hold the top of the smaller disk in alinement with the remaining disks in the cabinet. Any system may be used for indexing the containers such as disclosed in the above-named application. 85 In order that the container or construction of the container or envelop may be more completely understood reference is to be had to the accompanying drawings wherein two forms of containers or envelopes are 90 shown.

Referring to Figs. 1 to 4 inclusive, it will be seen that the container has a base portion 1 the lower edge of which may be straight or formed otherwise to coöperate with the bottom of a cabinet, while the upper edge thereof is of arcuate form as shown at 2, and may be provided with flat ends as shown at 3, the height of the base 1 from the bottom to the ends 3, being approximately, though not necessarily, one third of the height of the container. Secured upon the back side of the base 1, is a sheet of heavy paper 4, the upper portions of whose edges converge as at 5, to meet the top edge which is provided with a finger opening 6. The front of the base 1 has secured thereto a strip of thin but tough paper 7, the upper edges of which converge as at 8, to correspond to the lines 5, the top edge of the front sheet 7 being 110

bent back as at 9, so that the upper portion of the rear sheet 4 is visible to disclose any form of index label or name which may be carried by the upper edge of the back sheet 5 to indicate the name of the contained record.

As shown in Fig. 4, the base 1 has an appreciable thickness so that in order to secure the front and back sheets of the container it is necessary to bend edges thereof at right angles and secure the same by any suitable means, such as an adhesive. These sheets of paper are secured to each other at the edges for a distance approximately extending upwardly two thirds from the base beyond 10 which point they are not connected, and at which point there is provided a stay formed of textile fabric strip indicated at 10, this stay having the end 12 secured to the front sheet, and the end 11 secured to the rear sheet, while the intermediate portion 13 extends across the rectangular end of the container to prevent tearing and wearing of the paper.

If desired, there may be secured along the 25 lower edge of the base 1, a U-shaped strip 14, the vertical sides of which are secured to the lower edges of the sheets by any suitable means such as rivets shown at 15. The front face of the strip 14 may be provided with 30 any suitable designating characters shown in Fig. 1, which may be arranged in any desirable way with respect to openings 16 formed in the bottom of the strip 14 and in the base 1. The positioning members 18 and 35 19 shown in Figs. 8 and 9, respectively, may have their shanks 20 and 21 respectively inserted within any of the openings 16 in such a way as to bring the selector beneath a certain designation carried by the strip 14, one 40 of the selectors being arranged upon each end of the strip, so that it will be possible to arrange a cross reference system, such as shown in the application already referred to. The shanks of the selectors are prefer- 45 ably spaced slightly farther apart than the openings 16, so that the slightest pressure will be required for springing the notches 22 into the bottom of the strip 14 and in order to prevent a further movement of the selec- 50 tors within the base 1, that portion of the selectors just below the notches 22 is bent inwardly as at 23 in both forms of selectors. Each of the selectors may have one shank shorter than the other for the purpose of 55 readily inserting the selector within the bottom of the container.

In the preferred form of the invention it will be understood that a disk record may be inserted within the envelop bearing the 60 proper designation on the upper front face of the back sheet of paper and that the same may then be placed within the cabinet where the containers may have their upper corners turned down as in an ordinary card index, 65 the circular form of the record admitting of

the bending of the corners of the back sheet of paper to uncover the names of the records contained therein. It will be seen that by reason of the finger notch 6 and the fact that the upper edge of the thin front sheet 70 of paper is below the top of the record, it will be possible to withdraw any record desired from the cabinet containing a number of records closely packed together without disturbing the container or envelop. 75

As shown in Fig. 5, an arrangement is provided whereby smaller disks than that disclosed in Fig. 1 may be used, the means accomplishing this purpose being an auxiliary envelop or container formed with a 80 base 24, the lower edge of which is arcuate as at 25, to conform with the arcuate edge 2 of the base 1, while the upper edge thereof is arcuate as at 26 to conform with the size of the smaller disk record. The lower arcuate edge terminates in projections 27 on either side thereof which engage the ends 3 of the base 1 to prevent any rotary movement of the auxiliary envelop within the larger envelop. This auxiliary container 90 may be composed of a rear sheet of heavy paper 28, and a front sheet of thin but tough paper 29, and may be provided with a stay 30 comparable with the stay 10. The bases 1 and 24 are substantially the same thickness as the disk, and are made slightly longer than the diameter of the disk so as to prevent scarring or binding of the disk within a containing cabinet. The upper edges of the auxiliary envelop may be tapered as at 31, in a manner somewhat similar to the taper of the larger envelops, to permit easy turning back of the corners to disclose or uncover the names printed upon said envelops. It is to be understood of course that the auxiliary envelop may be made so as to contain any size disk the only requisite being that the base 24 of the auxiliary envelop be of such height as will place the tops of all of the records in alignment. 100 The auxiliary envelops are not so wide as the larger containing envelops for the purpose of allowing the auxiliary envelops to slip easily within the larger containers. 110

The form of the invention shown in Fig. 5 115 is not provided with the selector devices on the lower edge of the base and I wish it understood that these selectors may be used or omitted as the same form no essential part of the envelop, but are useful only in connection with an index system such as already referred to.

As shown in Figs. 1 to 4, the side edges of the base are substantially rectangular, but it will be possible as shown in Fig. 7, to bevel the edges of the base 1^a as at 32, so that the bevel face 32 and the back of the base meet practically in the line along which the front and rear sheets of paper may be glued together, in which event it may not 125 130

be necessary to use the stays shown in Fig. 10, but it would be still desirable to have approximately one third of the upper portions of the front and back sheets disconnected.

In Fig. 11, wherein an enlarged section of the upper portion of a standard container holding an auxiliary container is shown, it will be seen that the down-bent edge 9 of the front sheet 7 of the larger envelop covers the top of the front sheet 29 of the smaller envelop so that in opening the container to remove a record, or in bending back the edges thereof to disclose the names of the records, one strip only, will have to be handled with the fingers.

What I claim is:

1. A container for disk records comprising an envelop the bottom of which 20 forms to the shape of the disk and is adapted to hold the disk centrally within the container.

2. A container for disk records comprising an envelop, a block having an arcuate edge mounted within the envelop in the body thereof, the sides of the envelop adjacent the block being secured to said block.

3. A container for disk records comprising an envelop, the bottom of which has 30 mounted therein a block having an upwardly facing arcuate edge, the block being of a thickness substantially greater than the disk.

4. A container for disk records comprising an envelop, a block secured to the envelop in the bottom thereof, said block having an arcuate edge conforming to the shape of the disk, the block and envelop being of a substantially greater width than the disk.

40 5. A container for disk records comprising an envelop, a block secured to and mounted in the bottom of said envelop, the outer side edges of the block being beveled, the sides of the envelop being secured to the beveled edges of the block, the upper edge of the block being arcuate to conform to the shape of the disk.

6. A container for disk records comprising an envelop, the bottom of which is 50 formed to the shape of a disk record, and means removably mounted upon said bottom adapted to hold a smaller record centrally of the envelop.

7. A container for disk records comprising an envelop, a block secured to the bottom of said envelop and having an arcuate edge, and an auxiliary removable strip having the lower edge shaped to conform with the arcuate edge of the block and its upper 60 edge shaped to conform to a disk.

8. A container for disk records comprising an envelop, a block having an arcuate edge secured in the bottom of the envelop, and an auxiliary block carried by the arcuate edge of said block and within the en-

velop and removable therefrom, the upper edge of the auxiliary block being arcuate and having a radius less than the radius of the arcuate edge of the block secured to the envelop, said arc of less radius being centrally placed.

9. A container for disk records comprising an envelop, a block having an upwardly facing arcuate edge secured in the bottom of the envelop, an auxiliary block removably mounted upon the said arcuate edge, means formed on the auxiliary block adapted to engage portions of the stationary block adapted to prevent rotation of the auxiliary block, and an envelop structure secured to 75 the auxiliary block adapted to receive a disk.

10. A container for disk records comprising an envelop, the bottom of which is adapted to hold disks centrally with respect to the envelop, and a removable block held 85 by the bottom of the envelop adapted to hold a smaller disk centrally with respect to the envelop.

11. A container for disk records comprising an envelop, the bottom of which is 90 adapted to hold a disk centrally with respect to the envelop, and a removable block held by the bottom of the envelop adapted to hold a smaller disk centrally with respect to the envelop, and with its edge at the same 95 height as that of the first mentioned disk.

12. A container for disk records comprising an envelop structure, the bottom of which is conformed to the shape of the disk and adapted to hold the disk centrally with 100 respect to the envelop, the upper edges of the envelop being disconnected.

13. A container for disk records comprising an envelop the upper edge of which is open and portions of the side edges of which 105 are open, and means formed in the bottom of the envelop adapted to hold the disk centrally within the envelop.

14. A container for disk records comprising a substantially square envelop, means 110 formed in the bottom of the envelop adapted to center the disk, the top of the envelop being open and a portion of the sides adjacent the top being separated, the upper edge of the envelop being of slightly less 115 width than the bottom thereof.

15. A container for disk records comprising an envelop the front and back of which are of unequal height, means for holding the disk centrally within the envelop, the 120 upper ends of the front and back respectively of the envelop being separated, and the shorter side being adapted to allow the disk to project above its upper edge.

16. A container for disk records comprising an envelop, the bottom of which is 125 adapted to hold records centrally, and an auxiliary envelop of less height and width than the first mentioned envelop adapted to lie within the first mentioned envelop, said 130

auxiliary envelop adapted to hold smaller records centrally with respect to the first mentioned envelop.

17. A container for disk records comprising a block of greater thickness than the disk, sheets of flexible material secured to the front and rear faces of the block, said sheets being connected for a portion of the height of the container and being disconnected for the remainder of the height of

the container, and strips of fabric secured to said sheets and extending over the edge of the container between the open and closed portions of said edges.

In testimony whereof I affix my signature in presence of two witnesses.

JOSEPH E. RALPH.
